UNITED STATES PATENT OFFICE

99,277

DESIGN FOR A PHONOGRAPH CABINET

Paul M. Fuller, Chicago, Ill., assignor to The Rudolph Wurlitzer Manufacturing Company, Buffalo, N. Y., a corporation of New York

Application February 8, 1936, Serial No. 61,052

Term of patent 7 years

To all whom it may concern:

Be it known that I, Paul M. Fuller, a citizen of the United States, residing at Chicago, in the county of Cook and State of Illinois, have invented a new, original, and ornamental Design for Phonograph Cabinets, of which the following is a specification, reference being had to the accompanying drawing forming a part thereof.

The figure shown in the drawing is a front perspective view of the phonograph cabinet embodying my design.

That side of the cabinet not shown in the drawing is the same as the side shown and consists substantially of a straight panel section with the fluted front corner extending partly around the same.

I claim:

The ornamental design for a phonograph cabinet, substantially as shown, and described.

PAUL M. FULLER.
